US00D546807S

(12) **United States Design Patent** (10) **Patent No.:** **US D546,807 S**
(45) **Date of Patent:** **** Jul. 17, 2007**

(54) **MOBILE PHONE**

(75) Inventor: **Young Keun Lee**, Seoul (KR)

(73) Assignee: **Samsung Electronics Co., Ltd.** (KR)

(**) Term: **14 Years**

(21) Appl. No.: **29/259,498**

(22) Filed: **May 9, 2006**

(51) **LOC (8) Cl.** **14-03**

(52) **U.S. Cl.** **D14/138**

(58) **Field of Classification Search** **D14/137, D14/138, 147, 218, 341-347; 455/90.3, 455/556.1, 556.2, 575.1, 575.3, 575.4; 379/433.01-433.13; 361/814; 348/14.02**

See application file for complete search history.

(57) **CLAIM**

The ornamental design for mobile phone, as shown.

DESCRIPTION

FIG. 1 is a perspective view of the ornamental design of the present invention;

FIG. 2 is a front elevational view of the ornamental design of the present invention;

FIG. 3 is a rear elevational view of the ornamental design of the present invention;

FIG. 4 is a left side elevational view of the ornamental design of the present invention;

FIG. 5 is a right side elevational view of the ornamental design of the present invention;

FIG. 6 is a top plan view of the ornamental design of the present invention; and,

FIG. 7 is a bottom view of the ornamental design of the present invention.
